UNITED STATES PATENT OFFICE.

HARRY BRIDGMAN SMITH, OF BROOKLYN, NEW YORK.

EDGING-STRIP FOR PAPER BOXES.

1,114,054.

Specification of Letters Patent.

Patented Oct. 20, 1914.

Application filed January 24, 1913. Serial No. 743,959.

To all whom it may concern:

Be it known that I, HARRY BRIDGMAN SMITH, a citizen of the United States, residing at Brooklyn, in the county of Kings and State of New York, have invented new and useful Improvements in Edging-Strips for Paper Boxes, of which the following is a specification.

The present invention relates to certain new and useful improvements in embossed and lace-paper edging-strips or flies commonly employed in the manufacture of cardboard boxes, such strips being usually attached along one edge to opposite inner walls of the box at the upper edges thereof and having their free portions folded over parallel with the top of the box, the object of such edging-strips being to make the box and its contents more attractive, when the cover is removed.

These embossed or lace-paper edging-strips as heretofore made have been embossed or decorated for a portion only of their width, the remaining portion or attaching edge being left plain or undecorated.

When an edging strip is embossed for a portion only of its width the embossing operation has a tendency to distort or stretch the said embossed portion of the strip relatively to the plain or unembossed portion or attaching edge thereof and this causes the latter named portion to wrinkle, crease or pucker, thus rendering it difficult to smoothly apply the attaching edge of the strip to the inner wall of the box either by hand or by the use of machinery. Furthermore, edging strips of this type or construction, namely; those having parallel embossed and unembossed portions are open to other serious draw-backs or objections, as will appear, when it is attempted to apply them by machinery of that type wherein the supply of edging-strips are arranged in the machine in pack form and fed by automatic feed mechanism one at a time from the pack to the machine; one of the objects of the present invention is to obviate such objections and provide an edging strip especially adapted for both hand and machine application.

One known type of machine now quite extensively employed for applying edging-strips to boxes is that shown and described in the patent to Philip S. Smith, #825,009, dated July 3, 1906, in which machine there is employed a vertically movable pack-

supporting bed for supporting a supply of edging strips; a pair of alternately moving clamping members for alternately engaging the upper surface of the pack along its opposite longitudinal edges; a vertically movable gum-applying and strip-lifting stencil having a yielding face that operates to apply a stripe of glue along one edge of the uppermost strip of the pack and then lift said edge to bring it into proper position for attachment to the inner wall of a box, and a presser-block to press the pasted edge of the strip against and affix the same to said box wall.

When using a supply of the old style edging-strips in connection with the above type of machine it is possible to employ only a comparatively thin pack owing to the fact that the pack is of unequal thickness along the opposite edges that are to be engaged by the two aforesaid clamping members, such inequality in the thickness of the pack being due to the fact that the embossed portion of the edging-strips is materially thicker than the plain or unembossed portion. Obviously the more sheets employed in the make-up of the pack, the greater the inequality in the thickness of the pack at the opposite edges thereof, and this inequality varies accordingly as the embossed or lace patterns or designs vary in the different edging-strips. Inasmuch therefore as the two clamping members referred to are constructed to engage the opposite edges of the pack with substantially equal pressure and since they have substantially the same degree of movement, it is impossible to properly and satisfactorily operate the machine with the old style edging sheets except by employing a relatively thin pack of such sheets wherein the inequality in the thickness referred to is very small. This, however, is objectionable and materially reduces the daily output of the machine owing to the fact that the machine must be stopped frequently during a day's run in order to supply the new packs of strips. In order to obviate this objection and to materially increase the daily output of the machine, I

provide an edging strip that is embossed or decorated along both of its longitudinal edges, thus making the strip of substantially equal thickness at both edges, or from edge to edge if desired, so that when the strips are arranged in pack form, the pack will be of substantially equal thickness at both of

its longitudinal edges, or from edge to edge, as the case may be, hence a pack of considerable thickness may be placed in the machine and the clamping members referred to will 5 coöperate better with such a pack than with a very much thinner pack of the old style strips.

I prefer to emboss the longitudinal or attaching surface or portion of the strip in 10 such a way as to provide numerous air and glue cells or pockets along such portion or edge in order to assist in the lifting action of the stencil and to insure the application to the strip of an adequate quantity of adhesive to properly seal the same to the inner wall of the box.

In order to enable others to clearly understand, make and use my said invention I will now proceed to describe the same in detail reference being made for this purpose 20 to the accompanying drawing wherein—

Figure 1 is a plan view showing one method of making two continuous lengths of my improved edging strip at one operation. Fig. 2 is a transverse sectional view on an enlarged scale of one of the edging strips made according to the invention. Fig. 3 is a sectional view on an enlarged scale of a portion of a pack of blanks made 30 according to the invention. Fig. 4 is a perspective view of a box showing the edging strips applied thereto.

In manufacturing my improved edging strip I prefer to pass a strip or web of paper 35 per 1, of sufficient width to make two strips, between a pair of intergeared male and female embossing die-rolls (not shown) said die-rolls bearing any desired pattern or design in duplicate and which is imparted to 40 the strip along parallel lines. The strip is then severed centrally and longitudinally of its length as at 2, Fig. 1, to provide two strips of the same pattern and these are then cut in suitable box-lengths and arranged 45 in pack form as illustrated in Fig. 3, or the unsevered or duplicate pattern sheets may be cut in box-lengths and arranged in packs and sold in this form, leaving the box manufacturer to sever the packs longitudinally and centrally as they are required for 50 use.

As will be seen by referring to Fig. 2, which is an enlarged transverse sectional view of one of my improved edging strips, 55 the embossings are all of substantially equal depth so that the strip will have substantially the same thickness along its opposite edges, or from edge to edge, as the case may be, depending upon the particular design 60 imparted to the strip. Obviously when a plurality of the strips are superposed one upon another and properly nested so that the corresponding embossings in the several sheets will interengage one another the 65 pack thus made up will be equal in thick-

ness along its opposite longitudinal edge- 70 portions or from edge to edge, as more clearly shown in Fig. 3.

I prefer to emboss the longitudinal attaching portion or edge 3, of the strip in such a way as to provide numerous air and glue pockets or cells 4, which serve not only to impart proper thickness to that portion of the strip, but such cells or pockets also 75 rid or assist the suction action of the stencil embodied in the machine to lift the attaching edge of the strip and they also receive from the stencil an ample supply of glue to insure proper attachment of the sheet to the box.

I contemplate cutting the edging strips in suitable box-lengths and arranging them in pack form to be sold in this manner as an article of manufacture, and as the packs will be of substantially equal thickness 85 along both longitudinal edges, a pack of any desired thickness may be placed in the machine.

Obviously I do not wish to be understood as limiting myself to an edging strip having any particular pattern or embossed design, as these may vary to suit the taste; nor do I wish to be understood as limiting myself to any particular character or design of embossing at the attaching portion 95 or edge of the strip, as this may also vary, although I prefer to employ an embossing having a cellular characteristic.

The term "embossed" as herein employed in connection with the ornamental portion 100 of the sheet, is used in its broader sense and includes either raised, or raised and cut-out figures, such as lace-paper designs and the like.

What I claim is:

1. As a new article of manufacture, an ornamental edging strip for boxes, having an attaching edge for attaching said strip to the box, said attaching edge having embossings therein forming pockets to receive the attaching adhesive, said strip having ornamental embossings on the body thereof.

2. As a new article of manufacture, an ornamental edging strip for boxes, having an attaching edge for attaching said strip to the box, said attaching edge having embossings therein forming pockets to receive the attaching adhesive, said strip having ornamental embossings on the body thereof, 110 said edge embossing being arranged to produce substantially the same longitudinal contraction in said strip at different points on the width thereof to prevent puckering at said attaching edge.

3. As a new article of manufacture, an ornamental edging strip for boxes, having an attaching edge for attaching said strip to the box, said strip having embossings on the inner and outer edges thereof for producing a substantially equal thickening of 115

the strip on said edges whereby a supply stack of said strips superposed upon each other will be of substantially equal height on its opposite edges, thereby facilitating the automatic feeding of said strips from said stack.

In testimony whereof I have hereunto set

my hand in presence of two subscribing witnesses.

HARRY BRIDGMAN SMITH.
